HOUSING FOR METAL DETECTOR

Thomas H. Doss, P.O. Box 10563,
Houston, Tex. 77018

Filed Mar. 3, 1969, Ser. No. 15,991

Term of patent 14 years

Int. Cl. D10—99

U.S. Cl. D52—6

The figure is a perspective view of a housing for a metal detector, showing my new design.

The undisclosed portion of the circular inductor member is flat and plain.

I claim:

The ornamental design for a housing for a metal detector, as shown and described.
